J. P. MINTON

TRANSMITTER

Filed Sept. 5, 1919

Inventor:

John P. Minton

by J. Roberto

Atty.

UNITED STATES PATENT OFFICE.

JOHN P. MINTON, OF NEW YORK, N. Y., ASSIGNOR TO WESTERN ELECTRIC COMPANY,
INCORPORATED, OF NEW YORK, N. Y., A CORPORATION OF NEW YORK.

TRANSMITTER.

Application filed September 5, 1919. Serial No. 321,914.

To all whom it may concern:

Be it known that I, JOHN P. MINTON, a citizen of the United States, residing at New York, in the county of New York, 5 State of New York, have invented certain new and useful Improvements in Transmitters, of which the following is a full, clear, concise, and exact description.

This invention relates to transmitters and 10 particularly to a type of transmitter especially adapted for use in places where such apparatus is subjected to severe extraneous noises or vibrations set up by the rush of air.

15 In various places there is a demand for a transmitter which will operate efficiently in picking up the feeble voice waves and yet will not respond appreciably to extraneous sounds or to violent disturbances of the air.

20 Such a transmitter is a necessity in connection with the intercommunicating sets used on airplanes for communication between the pilot and the observer and also for wireless communication from the plane to a ground 25 station or to another airplane. The disturbances set up by the exhaust of the engine and the rush of air through the guy wires is so violent as to make audible speech impossible between the pilot and the ob-

30 server and telephone apparatus is provided as the necessary means of communication. The transmitters employed under this condition must operate satisfactorily on the faint sound waves when one talks into the 35 transmitter and yet not be appreciably affected by the extraneous noises. Again, in connection with telephone apparatus used for fire control, either on battle ships or on land fortifications, it is necessary that the 40 transmitter easily and intelligibly transmit speech even though subjected to the violent concussion due to the discharge of nearby batteries.

It is, therefore, an object of the present 45 invention to provide a transmitter which will operate efficiently on the feeble sound waves of the voice and which will not be affected appreciably by extraneous sounds.

It is a further object of the invention to 50 provide a transmitter which will not be affected appreciably by violent disturbances of the air occurring nearby.

A still further object of the invention is to 55 provide a transmitter of the type in question which will be cheap to manufacture,

will not have any delicate parts which will require expert attention and one in which the operating parts are protected from injury.

To accomplish these objects and in accordance with a feature of this invention, there is provided a transmitter in which means is provided for preventing vibrations outside of the range of useful voice frequencies from affecting the diaphragm and a resonant chamber is provided for magnifying the effect of vibrations coming within the range of useful voice frequencies. 60 65

This and other features of the invention will be more clearly understood by reference to the accompanying drawing, in which Fig. 1 is a sectional view of a transmitter embodying this invention, and Fig. 2 is a view in perspective of the various parts of the transmitter placed in position for assembly. 70 75

Referring now to the drawing, there is disclosed a cup-shaped casing 5 within which the transmitter button is mounted. The transmitter face plate comprising an 80 outer member 6 and an inner member 7 is secured to the cup-shaped member 5 by means of screws which pass through the countersunk holes 8-8 in member 6 and the perforations 9-9 in member 7, and thence into shouldered bushings 10-10 which are rigidly secured to the flanged portion of the aluminum casing 5. The bushings 10-10, which are preferably of nickel silver, are provided because of the 85 difficulty of forming threads in the aluminum casing and are of sufficient length to extend into suitable openings 11-11 in the spacer ring 12 and thereby prevent this ring from rotating. The ring 12 is provided with 90 a recessed portion 13 to allow sufficient clearance for the mounting of the damping spring 14 which is insulated from the casing 5 by means of insulating plates 15-15 of mica or other suitable insulating material. This spring is rigidly secured to the 95 casing by means of screws 16-16 and metal plate 17, the screws passing through suitable insulating bushings which are not shown in the drawing. The face plate 7 is provided on its inner side with a recessed portion to receive the diaphragm 18 and the insulating ring 19 which is preferably 100 oiled linen. The thickness of this linen ring determines the depth of the resonat-

105 110

ing chamber in front of the diaphragm and is preferably approximately twelve-thousandths of an inch. The central portion of member 7 is provided with a number of perforations 4-4 which are approximately forty-thousandths of an inch in diameter and lead from the inner resonating chamber next to the diaphragm to an outer resonating chamber 20 which is formed within the hub portion 21 on the outer side of member 7. The face plate member 6 is provided with a counterbored portion adapted to fit over the hub portion 21 of member 7 and a ring 22 preferably of oiled linen is provided 15 as shown in order to insure a tight chamber. The member 6 is provided at its center with a number of very small perforations 23-23, the diameter of these perforations being preferably approximately twenty- 20 thousandths of an inch, whereas the face plate at this portion is approximately thirty-two thousandths of an inch thick. The outer side of face plate member 6 is provided with a recessed portion adapted 25 to receive a disc 24 of coarse linen or other similar material adapted to prevent dust or moisture from entering and clogging the perforations 23-23. This linen disc is held in place by means of a plate 25 of hard 30 rubber or other suitable non-metallic material and the button-head screws 26-26 pass through the perforations 27-27 in plate 25 and engage the threads of corresponding perforations 28-28 in member 6. 35 Centrally located at the rear of the casing 5 is the shouldered bridge center 30, which is held in place by the lock nut 31 and is insulated from the casing by means of the insulating washers 32-32 and the insulating bushing 33. Located between the shouldered portion of the bridge center 30 and the outer insulating washer 32 is a metal plate 29 having an extended portion which is provided with a terminal screw 42. The 40 bridge center 30 is bored out to receive the shank 34 of a standard type of transmitter button comprising a cup member 35 in which are located the front electrode 36 and the back electrode 37, the remainder of the space being practically filled with granular carbon 45 which is held in place by means of the mica annulus 38 and the retaining nut 39. The front stud 40, which is in direct electrical contact with the front electrode 36, is held firmly against the center of the diaphragm 18 by the tension of the damping spring 14. After the transmitter has been assembled and the button properly located by the tension of spring 14, the button is locked in 50 position by tightening screw 41 which is threaded into the bridge center 30 and bears against the shank 34 of the transmitter button. A metal plate 44 is secured to the rear of casing 5 and insulated therefrom by 55 means of a plate 45 of hard rubber or other

suitable insulating material. This plate is provided with a right-angled stud portion 46 which extends into the interior of the casing through a suitable perforation 47. A conductor 48 extends from stud 46 to extension 49 of the damping spring 14, hence the screw 50 which threads into the plate 44 serves as a terminal member for the front electrode of the transmitter button. The other terminal screw 42 engages the plate 29 which is in direct electrical contact with the back electrode 37 but is insulated from the casing, hence in the transmitter as illustrated, the casing is not included in the electrical circuit. 70

Since in airplane service it often becomes necessary to use the transmitter at very low temperatures, plate 25 which is preferably of hard rubber or some other non-heat conducting material is provided for the purpose 85 of preventing the user from placing his lips in contact with any metal portion. This plate is provided at its center with a number of perforations 52 which are of comparatively large diameter and which may be in 90 alignment with the perforations 23-23 in plate member 6.

A transmitter of the type described has been found in service to be very satisfactory for use on airplanes, the construction being 95 such as to permit the efficient transmission of voice waves in spite of the disturbances set up by the exhaust of the engine and the rush of wind. This is accomplished by the combination of the auxiliary resonating chamber with the restricted openings on either side. The auxiliary chamber acts as a resonator for a band of frequencies within the limits of useful speech frequencies (for example 300 to 1800 cycles) and amplifies, 100 or rather intensifies, by sympathetic vibrations of the air within the chamber, the effect on the transmitter diaphragm of the voice sounds which are important. A large percentage of the disturbing noise is of a high 105 frequency nature, corresponding to the hissing noises produced by the exhaust of the engine and the whistling of the wind through the wires. The holes 23-23, due to their small diameter and appreciable 110 length, act as a filter or shield to prevent such vibrations from entering the resonating chamber 20. The natural frequency of this chamber is much lower than the frequency 115 of the vibrations to be eliminated, hence the chamber serves to further impede such vibrations, since its impedance to sound transmission increases with the frequency of the vibrations to be transmitted. Such vibrations are further filtered out by means of the small holes 4-4 in plate 7 and are further impeded by the thin resonating chamber between the plate 7 and the diaphragm 18. Vibrations of useful voice frequencies 120 are somewhat impeded by the small perfora- 125 130

tions 23 but are amplified by means of resonating chamber 20 which is so dimensioned as to be resonant at vibrations of voice frequency. The chamber between the plate 7 and the diaphragm 18 also acts as a resonating chamber and in addition provides a certain amount of air damping for the diaphragm 18.

It will, therefore, be seen that the combination of the small holes and the auxiliary chamber causes an increase in volume of the voice waves which it is desired to transmit and eliminates to a large extent the undesirable high frequency vibrations.

15 What is claimed is:

1. A telephone transmitter comprising a diaphragm, a plurality of chambers resonant at voice frequencies located in serial relation in front of said diaphragm and containing restricted openings connecting said resonating chambers.

2. A telephone transmitter comprising a plurality of resonating chambers, one of said resonating chambers being resonant to any desired band of vibrations within the voice frequency range for intensifying vibrations of a predetermined frequency within said range, and means for shielding each of said chambers from vibrations having a frequency outside of the range of vibrations it is desired to transmit.

3. A telephone transmitter comprising a diaphragm responsive to vibrations, and a plurality of chambers resonant at voice frequencies in front of said diaphragm, said chambers being of decreasing diameter outwardly.

4. A telephone transmitter comprising a diaphragm, a thin resonating chamber adjacent the diaphragm, an auxiliary chamber resonant to frequencies corresponding to voice vibrations, and a plurality of restricted openings connecting said chambers.

5. A telephone transmitter comprising a diaphragm, a face plate spaced adjacent to said diaphragm but separated therefrom to provide a thin chamber resonant at voice frequencies therebetween and an auxiliary chamber centrally located in the face plate, said face plate being provided with a plurality of small openings on either side of the auxiliary chamber.

6. A telephone transmitter comprising a diaphragm, a face plate adjacent thereto but separated therefrom to provide a thin resonating chamber, an air chamber resonant to vibrations within the range of voice frequencies centrally located in said face plate, means for preventing vibrations of frequencies outside of the voice range from entering said auxiliary chamber, and means between said chambers for further filtering out vibrations outside of the range of voice frequencies.

7. A telephone transmitter comprising a diaphragm, a plurality of chambers resonant at voice frequencies located in serial relation in front of said diaphragm, a plurality of sound filters separating said resonating chambers.

In witness whereof, I hereunto subscribe my name this 3rd day of September A. D., 1919.

JOHN P. MINTON.
